UNITED STATES PATENT OFFICE.

MAX HALPERT, OF NEW YORK, N. Y.

DESIGN FOR A VEGETABLE CABINET.

Application filed August 9, 1928. Serial No. 27,754. Term of patent 14 years.

To all whom it may concern:

Be it known that I, MAX HALPERT, a citizen of Hungary, and a resident of the city of New York, borough of Manhattan, in the county of New York and State of New York, have invented the new, original, and ornamental Design for a Vegetable Cabinet, of which the following is a specification.

I claim:

The ornamental design for a vegetable cabinet substantially as shown.

Signed at Brooklyn, N. Y., in the county of Kings and State of New York, this 30th day of July, A. D. nineteen hundred twenty-eight.

MAX HALPERT.
